US00D573178S

(12) **United States Design Patent**
Lee et al.

(10) **Patent No.:** US D573,178 S
(45) **Date of Patent:** ** Jul. 15, 2008

(54) **LASER COMPLEX**

(75) Inventors: **Son-Young Lee**, Seoul (KR); **Jun-Won Bae**, Seoul (KR); **Bong-Uk Lim**, Seoul (KR)

(73) Assignee: **Samsung Electronics Co., Ltd.**, Suwon, Kyunggi-Do (KR)

(**) Term: **14 Years**

(21) Appl. No.: **29/273,431**

(22) Filed: **Mar. 6, 2007**

(51) **LOC (8) Cl.** **18-02**

(52) **U.S. Cl.** **D18/50**

(58) **Field of Classification Search** D18/4.4, D18/36-39, 41, 50, 53, 54-55; D14/420, D14/462-470; 400/613, 613.1-613.4, 690.1-690.4, 400/691-694

See application file for complete search history.
